ELECTRONIC MODULATOR FOR CONSTANT
FREQUENCY VARIABLE DOT TRANSMIS-
SIONRobert Evart Shelby, Teaneck, N. J., assignor to
Radio Corporation of America, a corporation of
DelawareOriginal application September 14, 1936, Serial
No. 100,627. Divided and this application July
28, 1939, Serial No. 287,019

13 Claims. (Cl. 250—151)

This invention comprises a division of my original application Serial No. 100,627, filed September 14, 1936, which is now U. S. Patent 2,171,150.

In the past, facsimile experimenters have made use of a system of modulation in which the radio frequency carrier is modulated, or keyed, by a flat-topped supersonic wave of constant amplitude which has complementary, but not necessarily equal, variations in its positive and negative areas that are proportional to the modulation signal. Since the complete period of the supersonic wave remains constant while the rectangular "dots" or areas, comprising its positive and negative portions, vary in accordance with the modulation, this method has been given the name "constant frequency variable dot," or CFVD, modulation. More recently this same idea has been applied by Kell to the transmission of sound programs. The chief advantage claimed for the system is that it permits the use of voltage limiters in the receiver and thus gives a higher signal-to-noise ratio than is obtained when using the usual system of amplitude modulation under the same conditions. No attempt will be made here to discuss the merits of the system. This application is intended only to disclose a novel method of and means for producing CFVD modulation which it is believed has certain advantages over the methods now used.

In describing my invention, reference will be made to the attached drawings. In the drawings,

Figures 1 and 1a illustrate one form which the plate or target anode may take and the relation of the same to the other electrodes of an electron discharge gun or cathode ray tube used to produce CFVD modulation in accordance with my invention;

Figure 2 shows schematically the essential elements of my novel circuit for producing and applying potentials to the deflecting plates of an electron gun as illustrated in the prior figures and the mode of connecting the output of the novel circuit to the pairs of deflecting plates in an electron tube having a novel plate or target anode arranged in accordance with the present invention;

Figure 2a illustrates a phase shifter used in the circuit of Figure 2;

Figures 3a, 3b, 3c and 4 are curves illustrating the character of the output of an electron gun with an anode as indicated in Figures 1 and 1a

when the deflecting plates are excited as indicated in Figure 2;

Figure 5 shows a modified anode structure; while

Figure 6 is a curve representing the output of a system when the anode is as shown in Figure 5.

Figures 7, 7a, 8, 8a, 9 and 9a illustrate modified forms of final or target anodes.

In my United States application No. 72,916, filed April 6, 1936, entitled "Electronic modulator and method of modulation," a novel circuit and novel electron discharge device for producing phase and amplitude modulation is described. 15 In the present application and in the aforesaid application I use a novel electron gun or tube having a special target anode for converting amplitude modulated wave energy applied to pairs of deflecting plates into energy of the desired character for signalling purposes.

The term "electron gun" here, as in the prior application, has the meaning given to it by I. G. Maloff and D. W. Epstein in their paper entitled "Theory of electron gun," appearing in the Proceedings of the I. R. E., December 1934, page 1386. The circuit and device to be described here is in many respects similar in arrangement and operation to that disclosed in the said application. Here, however, the configuration of the final anode in the electron discharge device is different than that of the aforesaid application in order that CFVD output may be obtained in place of phase or amplitude modulation. Here, as in the said application, the tube illustrated diagrammatically in Figures 1 and 1a consists essentially of an electron tube 4, two sets of electrostatic deflecting plates 6 and 8, and a final anode 10. The target anode 10 is of special design. Figure 1a shows one form which the final anode 10 may have for production of CFVD modulation. The final anode or target 10 consists of two curved plates 14 and 16, having the complementary boundaries indicated by Figure 1, upon which the electrons from the electron gun 40 impinge. The electrodes 14 and 16 may consist of metallic plates or meshes or metallic deposits on the tube envelope or a surface supported in said tube. Where the electrodes 14 and 16 are of mesh a collecting electrode, not shown, may 45 be located back of the targets and properly charged relative to the other electrodes.

In order to obtain a CFVD signal, the plates 14 and 16 are caused to have the shape or form shown wherein the outer periphery of one side 50 of 16 follows a curve defined by $r = -a\theta - \delta$ while

the adjacent inner periphery of 14 follows a curve defined by $r = a\theta + \delta$. The other outer periphery of 16 may be defined by $r = -a\theta - \delta$ while the periphery or edge of 14 adjacent said last boundary is defined by $r = -a\theta + \delta$. In these equations r is the radial distance from the origin o to any point on the edge of the plate. θ is the angular displacement of the same point from a selected datum line which is the same for each curve; while a and δ are design constants, the latter depending on the spacing of the anode sections. In the modification illustrated, the datum line for the curves of the equations is shown by the broken line X. The equations given for the anode contours were departed from sufficiently near the origins to prevent the anode sections from becoming short-circuited.

In operation, the electron gun is controlled and focussed by adjusting the direct current potentials applied to the cathode, and to the control grid by 20, and to the screen grid and first anode by 22, just as in the case of oscilloscope tubes and kinescopes. The electron stream is sharply focussed on the final anode 10 and when there is no voltage applied to the electrostatic deflecting plates 6 and 8, it strikes the exact geometrical center of the final anode 10. The deflecting voltages, the nature of which and the manner of production of which will be described more in detail hereinafter, are such that they cause the electron stream to trace out a circle on the final anode 10, the diameter of the circle being a variable which is directly proportional to the instantaneous value of the modulation signal on the wave energy applied to the deflecting plates. When the plates 6 and 8 are excited by proper voltages, there will appear in Z_A a CFVD voltage characteristic of the modulating potentials used in producing the deflecting voltages. The deflecting voltages are preferably sinusoidal and of the supersonic frequency selected for the CFVD transmission. The deflecting voltages are obtained by phase displacing two portions of amplitude modulated wave energy. The manner in which the deflecting voltages are produced and applied to the plates 6 and 8 is shown in Figures 1 and 2 and will now be described, Figures 2, 3 and 4 being included in this application for illustrative purposes.

In Figure 2, voltages of substantially constant frequency and of sinusoidal form are supplied from any source to a modulator 21 of any known type. The oscillations may be produced by an oscillator of the crystal or line controlled type or of any other type, the only requirement being that they be of substantially constant frequency and constant alternating current amplitude. The modulator 21 may be of any type having the desired characteristics. The wave of sinusoidal form supplied to 21 is modulated in amplitude in accordance with the desired modulation signal impressed from any source on 21. The output of the modulator 21 is connected to an amplitude regulating potentiometer P_1 which is connected by a movable point to a phase shifting network 23. This network may take any suitable form, the essential feature being that the output thereof supplies two portions of the amplitude modulated wave in phase displaced relation. The amplitudes of the portions are substantially equal. Where the plates 6 and 8 are at right angles with respect to each other, the phase displacement of the deflecting voltages should be substantially 90°. Other angular relations between the deflecting plates requires other phase relations between

the deflecting voltages. One output from 23 goes directly to one set of deflecting plates. The other output from 23 goes to a potentiometer P_2 connected to the other set of deflecting plates. A preferred form of phase shifter is shown in Figure 2a. In this phase shifting circuit, the amplitude modulated radio frequency or carrier frequency waves are applied to input terminals and from said input terminals to a resistance 30 in series with condenser 32. By adjusting the condenser 32 and selecting the value of 30, the desired phase relation between e_1 and e_2 can be produced. The oscillations in 21 may be modulated in amplitude by facsimile signals, by keyed impulses, by voice frequencies, television or any other type of signals to produce constant frequency variable dot characters.

For a more detailed explanation of how the system works, refer now to Figures 1, 1a, 2, 2a, 3a, 3b and 3c. First, with no modulation input to 21, the phase shifting network in 23 and potentiometer P_2 of Figure 2 are adjusted so that the electron beam of the gun 4 describes a circle on the target or final anode 10. If the potentiometer P_1 is adjusted so that this circle is of the size designated by c_1 in Figure 1a, then the voltage appearing across Z_A , i. e., the output voltage will be as shown in Figure 3a. It will be noted that the electron stream passes from one segment, say 14, of the target anode to the other, say segment 16, and from the latter to the former at points P_1 and P_1' , which are 180° apart. This means that the positive and negative portions of each cycle of the flat-topped supersonic output voltage wave are equal, and this adjustment therefore corresponds to zero modulation. If now the two deflecting voltages from 23 are decreased in amplitude to almost zero by changing potentiometer P_1 , all other controls being left the same, the locus of the end-point of the electron stream will be c_2 of Figure 1a, and the voltage across Z_A will be as shown in Figure 3b. The electron stream now passes from one segment, say 14, of the anode to the other, say segment 16, and from the latter to the former at points P_2 and P_2' . Likewise, if the potentiometer P_1 is adjusted to give voltages almost double those which produced the locus c_1 then c_3 will be the new locus, the electron stream will pass from one anode segment to the other at points p_3 and p_3' and the voltage appearing across Z_A will be as shown in Figure 3c. Now, if P_1 is reset so that the electron circle falls on c_1 and amplitude modulation of almost 100% is then applied to the deflecting voltages in the manner indicated by Figures 1 and 2, the locus of the end-point of the electron stream will expand and contract between the limits c_2 and c_3 and the output wave will change its delineation, in accordance with the modulation signal between the two extremes shown in Figures 3b and 3c, the delineation of Figure 3a corresponding to zero modulation voltage. In this system, adjustment of circuit constants and monitoring of the system is facilitated by coating the target anodes or plates with willemite or other substance which fluoresces under the bombardment of the electron stream.

This device may be used to convert potentials of any frequency of sine wave form into voltages of flat topped wave form of equal frequency the duration of the dots of which can be adjusted through a wide range. This is accomplished by applying an unmodulated wave of sine wave form to P_1 and adjusting the same to make e_1 and e_2 of the desired value. The flat topped

wave so produced is of wide application in the radio and allied arts and is of particular value for television pictures and synchronization.

Figure 4 shows what a CFVD modulated flat topped supersonic wave looks like. In this example, the modulation is a sine wave the frequency of which is $\frac{1}{20}$ that of the supersonic wave, and the percent of CFVD modulation is 75. For radio transmission, this CFVD modulated voltage wave may be used to amplitude modulate or key a radio frequency carrier wave which may be used for signalling in any known system. A complete modulating system arranged in accordance with my invention has been shown in Figure 5 and will now be described.

Figure 5 illustrates one form of final or target anode for the electronic modulator or electron gun modulator which will give the modified CFVD modulation outlined above. It is practically the same as the one shown in Figures 1 and 1a except that a third target anode segment 115 has been added between the segments 14 and 16. The electrode 115 is electrically independent of the other two segments and is connected to the high voltage direct current supply source through an additional coupling impedance Z_B , across which the output appears comprising short sharp impulses.

Thus, as the electron stream passes from 14, say to 16, it first impinges on 115 and produces in Z_B a short sharp impulse of constant duration for all radial positions of the stream. Likewise, when the stream passes from 16 to 14 a short sharp impulse is produced so that each of the usual CFVD impulses is preceded and succeeded by the short impulses of equal duration. The form of the wave is shown in Figure 6.

It is noted in passing that the voltage appearing across Z_B in Figure 5 is similar to that produced across Z_A of Figure 1 being modified only by the action of 115 and Z_B as described above, and it is thus apparent that this one form of anode might be utilized for either type of CFVD modulation. The step by step analysis of the principle of operation will be omitted since it is so similar to the one given above for the anode of Figure 1. C_4 is the zero modulation circle and c_5 and c_6 are the limits between which the electron circle moves when the modulation is 75%. Figure 6 is an example of 75% modulation by the modified CFVD method. The modulating signal in this case is a sine wave, $\frac{1}{20}$ the frequency of the "dot" wave. For radio transmission the wave of Figure 7 is used to amplitude modulate or, optionally, to key the radio frequency carrier. For example, the modulated wave in Figure 7 may be applied to the grid electrode of a radio frequency amplifier to control its bias and key the tube.

Obviously, many variations are possible in the construction and utilization of this electronic modulator. To mention but two, electromagnetic instead of electrostatic deflection of the electron beam may be used, and the size of the electron circle may be varied by introducing the modulation signal into the anode supply circuits instead of modulating the deflecting voltages with it.

While I have shown the plate 16 of Figure 1a and plates 16 and 115 of Figure 5 as being located within plate 14, I contemplate the use of target anodes wherein 14 is a complete circle plate, while 16 is disposed in front of 14 as shown in Figures 7 and 7a. This structure simplifies pro-

duction because only one plate, i. e., 16, needs to be formed in accordance with my equation which may then be modified as shown in Figures 7 and 7a. With this form of final target, the wave form is improved because the electron stream falls substantially directly on 14 when it leaves 16 and vice versa. In other words, the constant δ is removed from the equation. The target of Figures 8 and 8a is particularly adapted to production of CFVD as is the anode or target electrode of Figure 1a. In this arrangement, electrode 14 may also be utilized as the collecting electrode to supplement or replace the action of electrode 98 of Figure 5 of my original application.

The same advantages of production can be obtained by using a target anode as illustrated in Figures 8 and 8a wherein the electrode 16' has a heart-shaped opening therein and the electrode 14' may have any peripherical contour so long as it completely covers said heart-shaped opening in 16'. This target arrangement is also particularly adapted to the production of CFVD.

It will be noted that in Figures 7, 7a, 8 and 8a, the electrode formed in accordance with my equation can follow the latter exactly from $r=0$ out since there is no radial spacing necessary between the edges of the plates to prevent short circuiting as in Figures 1a and 5.

For the production of modified CFVD or tuned impulse the target 115 may be placed in front of a plate 14 as shown in Figures 9 and 9a.

In each modification, the electrodes 14 and 16, and 14' and 16' and 115 may be coatings or deposits on the tube envelope properly separated by insulating material or supported thereby.

What I claim is:

1. An electron discharge device having a target anode comprising a plurality of surface bearing members arranged about a focal point, portions of the boundaries of one of said surface bearing members being defined by $r = \pm \alpha \theta + \delta$, portions of the boundaries of another of said surface bearing members being defined by $r = \pm \alpha \theta - \delta$; where r = radial distance from said focal point, α and δ are constants, and θ is angular deviation from a straight datum line through said focal point along which r is substantially zero.

2. An electron discharge device having a target comprising a plurality of superimposed surface bearing members arranged about a focal point, one of which surface bearing members is substantially of a shape defined by the intersection of two Archimedes spirals.

3. An electron discharge device having a target comprising two or more surface bearing members arranged about a focal point, one of said surface bearing members being substantially of a shape defined by the intersection of two Archimedes spirals and lying within the area of the other surface bearing member from which it is conductively separated.

4. An electron discharge device having a target comprising two or more surface bearing members arranged about a focal point, one of said surface bearing members being substantially of a shape defined by the intersection of two Archimedes spirals and lying within the projected area of the other surface bearing member.

5. An electron discharge device having a target comprising three surface bearing members arranged about a focal point, two of which surface bearing members are substantially of a shape defined by the intersection of two Archimedes spirals and disposed wholly within the area of

the remaining surface bearing member, all of said surface bearing members being conductively separated.

6. An electron discharge device having a target comprising three plates arranged about a focal point, two of which plates are substantially of a shape defined by the intersection of two Archimedes spirals and disposed wholly within the projected area of the remaining plate.

7. An electron discharge device having a target anode comprising a plurality of conducting elements arranged in a saucer-shaped surface about a focal point, at least one of said plates being substantially of a shape defined by the intersection of two Archimedes spirals.

8. In an electron discharge device, an electron emission element, a pair of anode electrodes, one of which is substantially of a shape defined by the intersection of two Archimedes spirals, in the path of emission from said emission element, and pairs of similar deflecting electrodes adjacent the path of said emission.

9. In an electron discharge device, an electron emission element, three anode electrodes, two of which are substantially of a shape defined by the intersection of two Archimedes spirals and located wholly within the area of the third electrode, and pairs of similar deflecting electrodes adjacent the path of said emission.

10. In an electron discharge device, an electron emission element, a pair of anode electrodes, one of which is substantially of a shape defined by the intersection of two Archimedes spirals, both of which are in the path of emission from said element, pairs of deflecting electrodes adjacent the 30

path of said emission and a collecting anode adjacent said anode electrodes.

11. In a discharge device, an electron emitting electrode, a target electrode comprising two conductive surface bearing members, a portion of the boundary of one of which is defined by $r = \pm \alpha\theta - \delta$ and a portion of another boundary of which is defined by $r = \pm \alpha\theta + \delta$ where r the radius from the electron stream focal point, α and δ are constants, and θ is the angular deviation from a straight line through said focal point where r is substantially zero and pairs of deflecting electrodes adjacent the path between said emitting electrode and said target electrode.

12. In an electron discharge device, an emission element, a pair of anode electrodes spaced therefrom and a plurality of anode electrodes in the path of emission from said element, one of said electrodes having an opening substantially of a shape defined by the intersection of two Archimedes spirals opening therein and being disposed between another of said anode electrodes and said emission element.

13. In an electron discharge device, an emission element, pairs of deflecting plates, a target anode comprising two conducting elements located around a focal point, a portion of the boundary of one of which conducting elements is defined by $r = \alpha\theta$, another portion of the boundary of the said one of said elements being defined by $r = -\alpha\theta$ where r is the radius from the electron stream focal point, α is a constant, and θ is the angular deviation from a straight line through the focal point where r is zero.

ROBERT EVART SHELBY.
